UNITED STATES PATENT OFFICE.

DANIEL E. HOFFMAN, OF PLYMOUTH, OHIO.

METHOD OF FORMING AND CONSTRUCTING THE MESHED ELEMENTS OF SEPARATOR-SIEVES.

1,386,335.

Specification of Letters Patent.

Patented Aug. 2, 1921.

Application filed October 14, 1919. Serial No. 330,579.

To all whom it may concern:

Be it known that I, DANIEL E. HOFFMAN, a citizen of the United States of America, residing at Plymouth, in the county of Rich-
5 land and State of Ohio, have invented cer-
tain new and useful Improvements in
Methods of Forming and Constructing the
Meshed Elements of Separator-Sieves, of
which the following is a specification.

10 This invention relates to a means and
method of forming and constructing the
meshed element of a separator sieve in sec-
tions so as to facilitate and expedite its con-
struction and eliminate the expense of mak-
15 ing dies of more or less complication which
is incidental to making and forming corrug-
ations or flanges on the meshed element.

Another object is to provide means of
20 making a meshed or perforated element for
a sieve of a series of sections and securely
fasten the same together without the use of
solder or the like. This application is a
continuation of a part of an application
25 filed Oct. 22, 1918, Serial No. 259,176.

These and other objects are attained by
the method illustrated in the drawing in
which:

Figure 1 shows in a conventional manner
30 a fragmentary view of the meshed or perfo-
rated sieve blanks assembled together pre-
paratory to fastening same to the end bars
of a sieve frame.

Fig. 2 shows a method of forming the
combined corrugated flanges and connecting
35 means in series preparatory to fastening
same together.

Referring to the drawing the meshed or
perforated element of the sieve is prefer-
ably made of three or more sections. The
40 method or means of constructing the meshed
element of the sieve comprises means of
connecting preferably three or more sections
together forming the entire meshed element.
In the construction of the meshed element
45 the desired number of blanks of sheet metal
to construct a predetermined size sieve are
first blanked out to form a plate substan-
tially of rectangular form as shown at 1.
One end of the blank is folded and then
50 double folded upon itself to provide a
strengthening rib 2, along the edge of each
of the outside meshed strips. The opposite
edge or end of the blank is then turned at
right angles to the body portion of the strip
55 as shown at 3.

The above described operations complete
the first or one outside portion (A) of the
movable meshed element. Another blank
(B) is then folded upon itself as shown at 4
and then turned at right angles to the body 60
portion of the blank, leaving an intervening
space 5 between the fold to receive and
engage the right angular portions 3 of the pre-
ceding blank (A), thereby securely connect-
ing the blanks together. Prior to connect- 65
ing the blanks, the end 6 of blank B is
turned at right angles to the body of the
blank, as shown in the drawings. As many
intervening blanks as desired to complete the
size of sieve wanted or ordered can be made 70
in the same manner by repeating the opera-
tion hereinbefore described. Only one con-
ventional intervening blank is shown. It is
apparent, however, that a plurality of inter-
vening blanks can be used without departing 75
from the spirit of the invention.

To complete the sieve, a blank C is pro-
vided, for the opposite outside edge forming
the body of the movable meshed element;
one edge 7 thereof is folded upon itself and 80
turned at right angles to the body portion
leaving an intervening space to receive and
engage the right-angled portion 6 of the
blank B; its opposite edge 8 is then double
folded in the same manner and for the same 85
purpose as described with reference to
blank A.

The blanks A, B, and C are apertured as
shown at 9 with apertures preferably rec-
tangular in form. A predetermined portion 90
of the ends 10 of the connected blanks how-
ever are not apertured so as to provide an
extra plane surface and means of securely
fastening the blanks by screws or the like
to the end bars. 95

Attention is called to the fact that the con-
necting means of the sections also provide a
series of ribs or corrugations 11 upon the
meshed element which greatly strengthens
the meshed element and further provides a 100
series of channels of predetermined widths
so as to guide and confine the grain, straw,
chaff, stems and the like in their travel over
the meshed element along well defined paths
which are of great assistance in thoroughly 105
performing the function of cleaning the
grain.

I claim:

1. The herein described method of con-
structing a sieve for threshing machines in 110

sections consisting of forming a meshed blank from sheet metal, then folding the blank at one edge upon itself leaving a space between the fold, then turning the folded portion at right angles to the body portion, then turning the opposite edge of the blank at right angles to conform and coincide with the right angled folded opposite edge portion of the blank, then connecting a predetermined number of the folded blanks together by inserting the turned angular edge of one of the blanks in space between the next succeeding or preceding angularly related folded portion of the adjacent meshed blank.

2. The herein described method of constructing a sieve for threshing machines in sections consisting of forming a meshed blank from sheet metal, then folding the blank at one edge upon itself leaving a space between the fold, then turning the folded portion at right angles to the body portion, then turning the opposite edge of the blank at right angles to conform and coincide with the right angled folded opposite edge portion of the blank, then connecting a predetermined number of the folded blanks together by inserting the turned edge of one of the blanks in the space between the next succeeding or preceding folded portions of the adjacent meshed blank.

3. The herein described method of forming a sieve for threshing machines consisting of forming a series of meshed blanks having one edge of each folded upon itself; then turning it at right angles to the body portion, then turning its opposite edge at right angles and connecting each one of the series to each other by inserting the right angularly related portions between the folded portions of the next succeeding or preceding units, as described and set forth.

4. The herein described method of forming a sieve for threshing machines consisting of forming a series of meshed blanks, having one edge of each blank folded upon itself; then turning it at right angles to the body portion; then turning its opposite edge at right angles and connecting each one of the series to the other by inserting the right angularly related portion between the folded portions of the next succeeding or preceding units.

5. The herein described method of constructing a meshed sieve element for separators in sections, by first forming meshed blanks of sheet metal; then folding one edge of each blank to provide a space between the folded parts; then bending the opposite end of the blank at right angles thereto; then inserting said bent edge in the space between the fold of the next preceding blank; and then connecting other similar blanks thereto in same manner in series to provide the size of meshed sieve element desired.

6. The herein described method of constructing a meshed sieve element for separators in sections by first forming meshed blanks of sheet metal; then folding one edge of each blank to provide a space between the folded parts; then bending the opposite end at right angles and inserting the bent edge of the blank in the intervening space between the folded parts of the next preceding blank; then connecting thereto similar blanks in series by the method described with reference to the first mentioned blanks of the same or different sizes; then constructing blanks by the method described with reference to the first mentioned blanks having one edge folded and bent at right angles to the body and having the opposite edge folded to form ribs; then connecting said blanks to the aforementioned blanks for side sections.

7. The herein described method of constructing a meshed element in sections by first forming meshed blanks of sheet metal; then folding the edge of the blanks leaving a space between the folded parts and bending same at right angles to the body portion; then bending the opposite edge of the blanks at right angles to the body portions; then inserting said bent edge in the intervening space between the folded parts of the next preceding blank; then providing and connecting side blanks having folded edge portions, which are also formed with imperforate portions at their opposite edges; then folding said last mentioned edges upon the body portion to form ribs substantially, as described and set forth.

8. The herein described method of constructing a meshed sieve element for threshing machines in sections, consisting of forming a series of sheet metal apertured blanks; then bending one edge at right angles to the body portion; then doubling the opposite edge upon itself to provide a fold leaving a space between the folded parts; then inserting the right angled bent portion between the parts of the next preceding blank; then connecting thereto a pre-determined series of said blanks by the method described with reference to the first mentioned blanks of the same or different sizes to provide the size of meshed sieve element desired; and then connecting blanks to said series of blanks for side sections which are provided with folded edge portions and oppositely disposed edge portions which are folded to form ribs as and for the purpose described.

9. The herein described method of constructing a meshed element consisting of forming a series of sheet metal blanks having apertures provided between the ends and having the end portions thereof imperforate; then connecting a series of said blanks together to provide a sieve of predetermined size; then connecting side sections of blanks having imperforate side portions and fold-

ing said imperforate portions to provide ribs as and for the purpose described.

10. The herein described method of making a completed meshed element for a sieve 5 by forming a series of sectional parts with apertures therein, then bending a loop on one edge thereof; then turning the opposite edge up at right angles to the body portion and then connecting two or more of said ele- 10 ments together by inserting the bent edge on the loop of the adjacent blank to provide a sieve of the desired dimensions substantially as and for the purpose described.

11. The herein described method of making a complete meshed element for a sieve 15 by providing a series of sectional parts with apertures therein, then forming a loop on one edge thereof and turning the opposite edge up at right angles to the body portion; 20 then inserting the bent edge in the intervening space between the loop parts of the next preceding blank; connecting a plurality of said elements together by the method described with reference to the first 25 mentioned blanks to provide a sieve of the desired size, and then connecting side blanks to said blanks which are provided with imperforate folded edges forming ribs substantially as and for the purpose described.

30 12. The herein described method of constructing a meshed element for sieves for threshing machines by forming a series of meshed parts; then providing means integral with said parts consisting of bending 35 one edge of the meshed parts at right angles to the plane of the body and forming folds at right angles to the plane of the body on the opposite edge to connect two or more of said parts in series to provide a predetermined size of a complete meshed sieve 40 element, and then connecting side parts to said series and folding a portion of said side parts to provide ribs substantially as and for the purpose described.

13. The herein described method of con- 45 structing a meshed element for threshing machines consisting in forming a series of meshed blanks; then forming a loop on one edge and a right angular flange on its opposite edge; then inserting the bent edge in 50 the intervening space between the loop part of the next preceding blank; connecting a plurality of said sections together by the method described with reference to the first mentioned blanks to provide a pre-deter- 55 mined size sieve element, and then folding a portion of the side sections upon itself to provide ribs substantially as and for the purpose described.

14. The herein described method of con- 60 structing a sieve for threshing machines consisting in forming a series of meshed blanks and providing integral means consisting of bending one edge of the meshed parts at right angles to the plane of the body and 65 forming a loop at right angles to the plane of the body on the opposite edge to connect same in series; then inserting the bent edge in the intervening space between the loop part of the next preceding blank the meshed 70 blanks having imperforate end portions.

15. The herein described method of con- 75 structing a meshed element for sieves for use in separators consisting of cutting blanks; then forming a series of apertures therein so as to leave the ends and sides thereof imperforate, then forming a loop at one side, and providing a flange upon the opposite side thereof; then inserting the bent edge 80 in the intervening space between the loop part of the next preceding blanks; then connecting by the method described with reference to the first mentioned blanks two or more of said blanks to provide a meshed sieve element of a predetermined size. 85

In testimony whereof I affix my signature.

DANIEL E. HOFFMAN.
